(57) **CLAIM**

The ornamental design for a communications appliance, as shown and described.

DESCRIPTION

FIG. 1 is a top view of a communications appliance of our new design;

FIG. 2 is a bottom view of FIG. 1;

FIG. 3 is a left side view of FIG. 1;

FIG. 4 is a right side view of FIG. 1;

FIG. 5 is a back view of FIG. 1;

FIG. 6 is a front view of FIG. 1;

FIG. 7 is a right side, top and front perspective view of FIG. 1;

FIG. 8 is a right side, top and front perspective view of FIG. 1 with the housing open; and,

FIG. 9 is a right side, top and back perspective view of a communications appliance of our new design shown in an alternative environmental use.

The broken lines are for illustrative purposes only and form no part of the claimed design.
